UNITED STATES PATENT OFFICE.

WILLIAM H. EMOND, OF NEWTONVILLE, MASSACHUSETTS.

DESIGN FOR A VEHICLE-BODY.

40,420.

Specification for Design. Patented Dec. 28, 1909.

Application filed October 13, 1909. Serial No. 522,499. Term of patent 7 years.

To all whom it may concern:

Be it known that I, WILLIAM H. EMOND, a citizen of the United States, and resident of Newtonville, in the county of Middlesex, State of Massachusetts, have invented a new, original, and ornamental Design for a Vehicle-Body, of which the following description is a specification, reference being had to the accompanying drawing, forming part thereof.

Figure 1 is a side elevation showing my new design; and Fig. 2 a rear end elevation thereof.

I claim:

The ornamental design for a vehicle body as shown.

WILLIAM H. EMOND.
